UNITED STATES PATENT OFFICE.

WILLIAM EIBEL, OF RHINELANDER, WISCONSIN, ASSIGNOR TO EIBEL PROCESS COMPANY, OF BOSTON, MASSACHUSETTS, A CORPORATION OF MAINE.

FOURDRINIER MACHINE.

No. 851,227.

Specification of Letters Patent.

Patented April 23, 1907.

Application filed February 28, 1907. Serial No. 359,709.

To all whom it may concern:

Be it known that I, WILLIAM EIBEL, of Rhinelander, county of Oneida, State of Wisconsin, have invented an Improvement 5 in Fourdrinier Machines, of which the following description, in connection with the accompanying drawings, is a specification, like characters on the drawings representing like parts.

In Fourdrinier machines, as heretofore constructed and arranged, the paper stock is constantly fed to the flow-box from which it flows into the stock-reservoir which opens out of the flow-box and which extends for a 15 short distance over the breast roll end of the paper-making wire. The stock is then delivered upon the wire, through one or more (usually two) narrow horizontal openings which are provided at the bottom of that end 20 of the stock-reservoir opposite the flow-box. The stock is caused to rise in the stock-reservoir to a considerable height and is purposely maintained at a substantial elevation. As a result the stock issues from the narrow 25 horizontal orifice with considerable velocity due to the pressure of the column of stock in the stock-reservoir, commonly called the head. The stock thus forcibly issuing from the orifice causes a violent commotion on the 30 wire, immediately in front of the stock-reservoir, which is very objectionable. Furthermore the weight of the large volume of stock in the stock-reservoir is sufficient to spring or bend the small rolls which support the wire 35 in front of the breast-roll, and the forcible issuance of the stock from the stock-reservoir also acts to spring or bend the small rolls which support the wire immediately in front of the stock-reservoir. Such springing 40 or bending of the wire-supporting rolls at the bottom of the stock-reservoir in front of the breast-roll and also in front of the stock-reservoir is objectionable; the truer they turn the better. Also, heretofore, the stock, 45 which is fed constantly to the flow-box, rises in the flow-box with considerable commotion and as it flows into the stock-reservoir it does not maintain a level therein but produces a commotion in said reservoir and the stock in 50 said reservoir, is consequently in a state of great agitation resembling violent boiling.

This invention has for its object to construct and arrange the flow-box and stock-

reservoir and its delivery orifice of a Fourdrinier machine in such manner that the 55 stock will rise evenly and uniformly in the flow-box and will flow into and along the stock-reservoir with little commotion, in a shallow stream maintaining a smooth and substantially constant surface, and will be 60 delivered upon the wire with little or no commotion immediately in front of the stock-reservoir, thereby permitting the fibres and other paper forming ingredients to begin to settle on the wire immediately, resulting in 65 improving the formation of the paper on the wire and also in obviating springing or bending the small wire-supporting rolls in front of the stock-reservoir; and, at the bottom of 70 the stock-reservoir.

Figure 1 shows in vertical longitudinal section the flow-box and stock-reservoir embodying my invention and a portion of the paper-making wire. Fig. 2 is a plan view of the flow-box and stock-reservoir and paper-making wire shown in Fig. 1. Fig. 3 is a detail, showing in front elevation a portion of the stock-reservoir.

a represents the usual Fourdrinier wire or paper-making wire; which is downwardly inclined according to my Patent No. 845,224 dated Feb. 26, 1907; *b* the breast-roll; *d* the small tubular rolls which support the paper-making wire between the breast-roll and the guide roll, the latter not being herein shown. 85

e represents the flexible apron which is attached to the apron board *e'*, and which extends over said board and over the end portion of the wire at the breast-roll, terminating at a point close to or beneath the slicer *f*. 90 The said apron forms the bottom of the stock-reservoir and the slicer *f* one end thereof, while *f'*, *f''* represent its side walls; which extend from the slicer to the flow-box.

The apron board *e'* is attached to the front 95 wall of the flow-box at the top.

The flow-box comprises the front wall *g*, rear wall *g'*, side walls *g'', g''*, and contains within it several partition walls, three being herein shown, as *g³*, *g⁴*, *g⁵*, which divide the 100 flow-box into four vertical compartments.

The stock first enters the compartment formed between the rear wall *g'* and the partition wall *g³*, it flowing over the top of said rear wall *g'* into said compartment, and said 105 partition wall *g³* is so placed in the flow box

and made of such dimensions as to provide an opening beneath it for the passage of the stock into the compartment formed between the partition walls g^3 and g^4 , and said partition wall g^4 is so placed in the flow-box and made of such dimensions as to provide a passage above it for the stock into the compartment which is formed between the partition walls g^4 and g^5 , and said partition wall g^5 is so placed in the flow-box and made of such dimensions as to provide an opening beneath it for the passage of the stock into the compartment formed between the partition wall g^5 and the front wall g of the flow-box. The several compartments are made of different widths to provide for an increase in the volume of stock, as for instance, each successive compartment is made wider than the preceding one. An outlet is provided for each compartment, except the last one of the series, and in operation said outlets are closed. They are provided for the purpose of cleaning out the box, when the machine is at rest, although the outlet of the first compartment of the series may be connected by a pipe with the pump.

By providing a series of compartments, as herein shown, the stock becomes more uniformly and thoroughly mixed, which is particularly desirable if additional water is supplied while it passes through the flow-box. Near the top of the last compartment of the series, as for instance, between the partition wall g^5 and the front wall g , a perforated plate is placed, which is arranged obliquely to a horizontal plane and the stock passes up through the perforations in said plate. By means of the several partition walls which divert the flow of stock and the perforated plate the stock rises in the last compartment of the series with little commotion and is quite free from bubbles, so that it will flow into and along the stock-reservoir in a shallow stream evenly and uniformly and will maintain a substantially constant level therein.

It is not herein intended that the stock shall accumulate in the stock-reservoir, to produce a head, and to provide for thus controlling the volume of stock in the stock-reservoir the horizontal opening at the bottom of the stock-reservoir, at that end opposite the flow-box, is made very large to thereby permit the stock to escape as fast as it enters the stock-reservoir, only holding back sufficient stock in the reservoir to maintain the lower edge of the slicer in constant engagement with the stock and prevent the escape of froth and bubbles in excessive amounts.

With my improved flow-box and the machine otherwise arranged according to my present invention the surface of the stream of stock flowing through the reservoir will be so smooth and so regular in depth that the slicer will need to penetrate but very slightly below its top level. The slicer should never be lowered more than is necessary to accomplish this result.

If the slicer should be lowered the stock will accumulate in the stock-reservoir and produce a head, and if the slicer should be raised its engagement with the stock will be broken. By thus constructing and arranging the flow-box and slicer the objects of my invention are accomplished, viz., the stock rises in the flow-box without commotion, is delivered to the stock-reservoir evenly and uniformly, and is then delivered upon the wire in front of the stock-reservoir with little or no commotion on the wire whatsoever, and the small wire-supporting rolls at the bottom of the stock-reservoir, in front of the breast-roll, and also in front of the stock-reservoir will not be sprung or bent.

Having thus described my invention, what I claim as new and desire to secure by Letters Patent is:—

1. A Fourdrinier machine having a downwardly moving paper-making wire and a stock-reservoir with its slicer disposed with its lower edge just below the top level of the stock flowing through said reservoir, substantially as described.

2. A Fourdrinier machine having a flow-box in open communication with the stock-reservoir and a perforated plate obliquely arranged in one of its compartments, substantially as described.

3. A Fourdrinier machine having a flow-box in open communication with the stock-reservoir comprising a plurality of compartments, alternately arranged in open communication with each other at the top and bottom, a perforated plate obliquely arranged in one of said compartments and a downwardly moving paper-making wire and a slicer disposed with its lower edge just below the top level of the stock flowing through the reservoir, substantially as described.

In testimony whereof, I have signed my name to this specification, in the presence of two subscribing witnesses.

WILLIAM EIBEL.
